Fig. 1.

Fig. 2.

Fig. 3.

Fig. 4.

Fig. 5.

FIGURE 1 is a side elevational view of the combined oven and grill for outdoor use showing my new design, the opposite side thereof being substantially the same in appearance;

The dominant features of my design reside in the portions shown in full lines.

I claim:

The ornamental design for a combined oven and grill for outdoor use, as shown and described.
